UNITED STATES PATENT OFFICE.

WILLIAM MALLINSON, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,790, dated April 16, 1872.

Specification describing a new and original Design for a Carpet, invented by WILLIAM MALLINSON, of Halifax, in the county of York, England.

The accompanying photograph fully represents my new design.

This invention relates to a new design for the groundwork of a carpet and its border.

The groundwork or main part of the carpet consists of squares arranged between narrow strips that are subdivided into parallelograms and small squares, the latter being at the corners of the main squares, respectively. The several parts are ornamented as shown. The

border of the carpet is conspicuous on account of the row of lozenge-shaped figures it contains, the same being formed by intersecting zigzag lines, as shown.

I claim as my invention—
1. The design for the groundwork of a carpet, as shown.
2. The design for the border of a carpet, as shown.

WILLIAM MALLINSON.

Witnesses:

W. H. RANKIN,
GEORGE HENRY HOYLE.
